[57] **CLAIM**

The ornamental design for a credenza, as shown and
described.

DESCRIPTION

FIG. 1 is a perspective view of the credenza showing
our new design;

FIG. 2 is a front elevational view thereof, the back and
bottom being plain and unornamented;

FIG. 3 is a top view thereof, the back and bottom being
plain and unornamented;

FIG. 4 is side view thereof with the opposite side view
being a mirror image thereof; and,

FIG. 5 is a front elevational view of an alternate em-
bodyment of the credenza showing our new design, the
top, sides, back and bottom being similar to that shown
in FIGS. 3 and 4 but modified to reflect lengthening of
the first embodiment by one module thereof.
